[57] **CLAIM**

The ornamental design for a computer station enclosure, as shown and described.

DESCRIPTION

FIG. 1 is a front left perspective view of the computer station enclosure in accordance with my invention;
FIG. 2 is a front elevational view thereof;
FIG. 3 is a rear elevational view thereof;
FIG. 4 is a right side elevational view thereof;
FIG. 5 is a left side elevational view thereof; and,
FIG. 6 is a top view thereof.

No claim is made to the appearance of the microscope. The dashed lines in FIG. 1 are to illustrate a potential environment in which the invention might be used and do not form a part of the invention.

1 Claim, 3 Drawing Sheets

*FIG. 1**FIG. 2**FIG. 3**FIG. 4**FIG. 5**FIG. 6*UNITED STATES PATENT AND TRADEMARK OFFICE
CERTIFICATE OF CORRECTION

PATENT NO. : Des. 435,548
DATED : December 26, 2000
INVENTOR(S) : Treadwell

It is certified that error appears in the above-identified patent and that said Letters Patent is hereby corrected as shown below:

Cover page, [75], "Etobicoke," should read --Etobicoke, Ontario--

Signed and Sealed this

Fifteenth Day of May, 2001
